UNITED STATES PATENT OFFICE

LESLIE S. HUBBERT, OF EDISON, OHIO, ASSIGNOR TO THE HYDRAULIC PRESS MANUFACTURING COMPANY, OF MOUNT GILEAD, OHIO

HYDRAULIC PLASTIC PRESS

Application filed January 17, 1928. Serial No. 247,425.

This invention relates to improvements in the type of press disclosed in Patent No. 1,567,766, granted December 29, 1925, to T. F. Stacy, and particularly relates to an improved mechanism for tilting the upper press head and for giving the lower press table a sliding movement into and out of its operative position. These two movements are to bring the head and table into a position more accessible to the operator.

The mechanism for producing both of these desired movements comprises double acting hydraulic cylinders of the differential type, and hydraulic piping is connected to each so that a constant pressure is exerted against the small end of the rams which slide in the cylinders. Means is provided whereby these members can be moved out of the pressing position by means of pressure admitted through an automatic valve to the large end of each cylinder.

Further details of the invention will be apparent from the following description and the appended claims.

In the drawings:

Figure 1 is a side elevation of a press, including the present invention.

Figure 2 is a horizontal section taken on the line 2—2 of Figure 1.

In many respects, the type of press to which the invention is applicable may be widely varied, but there is shown herein a press having a base A supporting the platen B, which is movable upward to bring the dies carried thereby in contact with an upper press member supported by the head C of the press. The upper and lower members of the press frame are preferably connected by four strain rods D. There may also be provided pullback or stripping cylinders E which return the platen B to its lowermost position. These parts are or may be substantially similar to those shown in the above entitled patent, or may be varied as desired.

The lower press member comprises a table 1 which is adapted to slide on guideways 2 carried by the vertically movable platen B. This table has a cylinder 3 formed integral therewith, the cylinder opening projecting through the table and being lined with a

tubular member 4. Opposed ends of the cylinder are closed by packings 6 and 8 respectively held in place by gland nuts 5 and 7. It will be noted that the platen B is also a support upon which the table 1 is carried.

A hollow piston rod 9 is held in a supporting member 10 carried by the press frame and has lock nuts 11 and 12 screw threaded thereon on each side of the member 10. This hollow piston rod passes through an opening in the gland 5, and at its inner end is screw threaded at 13 into a piston head 14 provided with suitable packing 15 between the outside thereof and the wall of the hollow piston rod 4. A pipe 16 passes concentrically through the piston rod to form a resultant space between the piston rod and the pipe, and suitable compression packing 17 is provided around the pipe at its outer end. At its inner end the pipe 16 is screw threaded into the piston head 14 and the pipe connects with a passageway 18 through said piston head, which opens into a chamber 19 at the inner end of the cylinder 4. A pipe 20 passes through the wall of the piston rod 19 outside of the cylinder 4 and permits fluid under pressure to flow into the space within said piston rod surrounding the pipe 16. Near the inner end the piston rod is provided with an opening 21 which communicates with the chamber of the cylinder 4 on the outside of the piston rod 9.

In the position shown in Figure 2, the table is in its inner or operative position, and if it is desired to slide the table to the outer position, where it will be accessible to the operator, fluid under pressure will be admitted to the pipe 16 and passage 18 into the chamber 19. Since the piston rod 9 and piston 14 are held against endwise movement, the pressure of the fluid will cause the table to move toward the left of Figure 2 to its outer position. When the table is to be moved back into the inner position, pressure will be released from the chamber 19 and fluid under pressure admitted through the pipe 20 and opening 21 into the space surrounding the piston rod 9, and will exert its pressure against the head 23 at this end of the cylinder, which, it is to be noted, is approximately one

half the area of the head formed by the chamber 19. The table will therefore be returned to its inner or operative position. Due to the fact that the piston rod passes through one end of the cylinder the effective area of that end is less than that of the other so that pressure may be constantly contained in the pipe 20, since, when pressure is admitted to the pipe 16, it will act against a head substantially twice as great as that of the other head, so that the table may be moved outwardly, notwithstanding the fact that the fluid under pressure entering through the pipe 20 tends to return the pipe to its inner position. It is to be noted that while the table 1 is normally disposed between the platen and the press head C, it is adapted to be moved laterally toward the front of the press to a projected position. The means for thus moving the table are connected to the support upon which the table slides, at the rear end only of the press so that said means do not in any way interfere with the operator who stands at the front of the machine.

The present invention also comprises a different means for operating the upper tilting platen or press head. A double acting cylinder 24 is provided with a piston rod 25, which carries intermediate its ends a member 26 having a slot 27 therein. A pin 28 works in this slot and is carried by a crank arm 29 which is fastened to the trunnion 30 of the tilting platen head. It is obvious that a right line movement of the piston rod 25 will result in rotating the platen head 31 through the desired angle, which is preferably about ninety degrees.

It is obvious that any desired form of stops may be employed to limit the movements of the table and the tilting head in each direction. Both the table and the tilting head are formed with T-slots in the usual manner for the attachment of dies, and they may be equipped with any desired form of knockout devices. The sliding table may be equipped with adjustable gibbs for taking up lost motion or wear. The movable platen which carries the table and the main ram are returned to lower position by gravity, assisted by the auxiliary hydraulic cylinders E.

Although not strictly a portion of the present invention, it may be noted that the present press is automatically controlled by a motor-driven valve which causes the following operations to take place in sequence during one complete revolution of a motor-driven cam shaft.

1. The press head and sliding table are moved into pressing position, since at this time the large end at each differential auxiliary ram is connected to the exhaust, thus allowing the pressure to act on the opposite or small end of the rams.

2. The valve thereupon stops and after a final inspection the operator trips the auto-

matic lever and the cycle proceeds automatically.

3. Steam is admitted to the chambers of the dies.

4. The dies are closed and the main ram moved upwardly under low hydraulic pressure.

5. High hydraulic pressure is applied to the system.

6. Steam is cut off and cold water circulated through the die chambers. Both the steam exhaust and the water connections are operated through the automatic valve.

7. Hydraulic pressure is released from the main cylinder.

8. Hydraulic pressure is applied to the auxiliary cylinders, which return the main ram and platen.

9. During the opening of the press, hydraulic pressure is applied to revolve the head and slide the table out of pressing position so that the operator may quickly remove the finishing pieces, clean the die cavities, and place inserts and raw molding materials for the starting of the next operation. In each case the operation is initiated by tripping a lever which closes an electrical circuit and starts the valve motor. The duration of the entire cycle is regulated by proper gearing provided for the motor shaft and the valve operating cam shaft.

It is thus apparent that the present invention can be applied to a press of this character in order to perform the desired operations at the desired point in the cycle of operation of the press. It is also apparent that the invention may be applied to presses of different characters which may operate on somewhat different principles, and that various details of construction and arrangement can be changed without in any way departing from the spirit of the invention. It is particularly to be noted that the invention is to be regarded as limited only by the scope of the appended claims.

I claim as my invention:

1. In a molding press, the combination with a supporting framework, of a support mounted on said framework, a table slidably mounted on the support, a differential hydraulic cylinder having opposed ends rigidly carried by said table, a piston mounted in the cylinder, a hollow piston rod rigidly connected to the piston and to said support, said piston rod passing through one end of the cylinder whereby the effective area thereof is less than that of the opposite end, a pipe connected to one side of the piston and communicating with the cylinder on the other side of the piston for admitting fluid under pressure to the cylinder on that side of the piston, said pipe being concentrically located within the hollow piston rod to form a resultant space between the pipe and the wall of the rod, said rod being provided with an

opening communicating with said space and with the cylinder on the side of the piston opposite that with which said pipe communicates, means closing the ends of said space, and means for admitting fluid under pressure to said space.

2. In a molding press, the combination with a supporting frame, of a stationary press head carried by the framework, a reciprocatory platen mounted for reciprocation with respect to the framework, a support mounted on the platen, a table slidably mounted on the support and normally disposed between the platen and the press head, and means for sliding said table laterally and forwardly from its normal position to a projected position at the front of the press and for returning said table to its normal position, comprising a differential hydraulic cylinder having opposed ends rigidly carried by said table, a fixed piston mounted in the cylinder, a piston rod rigidly connected to the piston and to the said support at the rear end only of the press, said piston rod passing through the rear end of the cylinder whereby the effective area thereof is less than that of the opposite end, means for admitting fluid under pressure to the cylinder on one side of the piston and means for admitting fluid under pressure to the cylinder on the other side of the piston.

3. In a molding press, the combination with a supporting frame, of a stationary upper press head carried by the frame work, a platen mounted for reciprocation with respect to the frame work, a table slidably mounted on the platen and normally disposed between the platen and the press head, means for sliding said table laterally and forwardly from its normal position to a projected position at the front of the press and for returning said table to its normal position, comprising a differential hydraulic cylinder rigidly carried by said table, a fixed piston mounted in the cylinder, a piston rod rigidly connected to the piston and to said platen at the rear end only of the press, a tiltable head provided with a trunnion journaled in said stationary upper head for swinging movements about a horizontal axis and having a die supporting surface normally disposed in parallelism with said table and facing the normal position thereof, and means for swinging said tiltable head from its normal position to a position in which said die supporting surface faces the projected position of said slidtable table, comprising a crank arm on said trunnion, a hydraulic cylinder fixed to said frame work and arranged to operate a reciprocable piston rod, and connections between said crank arm and said piston rod.

4. In combination, a support, a table slidably mounted thereon, a differential hydraulic cylinder carried by said table, a piston

mounted in the cylinder, a hollow piston rod rigidly connected to the piston and to said support and extending through one end of the cylinder whereby the effective area thereof is less than that of the opposite end, a pipe connected to one side of the piston and communicating with the cylinder on the other side of the piston for admitting fluid under pressure to the cylinder on that side of the piston, said pipe being concentrically located within the hollow piston rod to form a resultant space between the pipe and the wall of the rod, said rod being provided with an opening communicating with said space and with the cylinder on the side of the piston opposite that with which said pipe communicates, means closing the ends of said space, and means for admitting fluid under pressure to said space.

In testimony whereof, I have hereunto subscribed my name.

LESLIE S. HUBBERT.
